(57) CLAIM

The design for a bag for strollers and walkers, as shown and described.

DESCRIPTION

FIG. 1 is a perspective view from the front and right of a bag for strollers and walkers;

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof; and,

FIG. 8 is a perspective view from the front and right of the bag of FIG. 1 with straps in an open position.

The broken line showing of a strap fastener is for illustrative purposes only and forms no part of the claimed design.
